UNITED STATES PATENT OFFICE.

FREDERICK D. McGINLEY, OF PLEASANT BEACH, NEW YORK.

CAR-REPLACER.

1,382,105.

Specification of Letters Patent. Patented June 21, 1921.

Application filed October 21, 1919, Serial No. 332,245. Renewed May 10, 1921. Serial No. 468,203.

To all whom it may concern:

Be it known that I, FREDERICK D. McGINLEY, a citizen of the United States, of Pleasant Beach, in the county of Onondaga, in 5 the State of New York, have invented new and useful Improvements in Car-Replacers, of which the following, taken in connection with the accompanying drawings, is a full, clear, and exact description.

10 This invention relates to certain improvements in car replacers adapted to be used more particularly for replacing electric cars on interurban railways in which portions of the rails project some distance above the 15 road bed as in suburban districts while in the cities and villages the surface of the rails is substantially flush with the surface of the pavement, and one of the objects of my invention is to provide a replacer adapted to 20 be used under either of those conditions.

In most cars of this type the front and rear ends of the body are mounted upon what is commonly known as four-wheeled trucks in which the axles, each carrying a 25 pair of wheels, are rigidly held in parallelism while the truck as a whole is pivotally connected near its center to the body of the car, and in most of the car displacements, the front wheels are usually the first to leave 30 the track when the car is in motion, thereby causing the truck to assume a greater or less angle to the line of the track, while on the other hand, in replacing the car it is customary to reverse its direction of motion so 35 as to bring the displaced wheels closer to their respective rails where they are easily replaced by the use of suitable replacers.

In replacing a displaced car upon a track, it is customary to employ a replacer for each 40 wheel of the same axle, the object being to elevate the wheels a sufficient distance to bring the flange of the outermost wheel and the tread of the other wheel above the ball of the rail when the rails are raised above 45 the pavement and to then direct the wheels into alinement with their respective rails as the motion of the car is reversed from that during which it was displaced.

It is well known that if a circular body 50 is rolled in a plane at an angle to and against a straight raised surface it will be gradually deflected by said surface until it runs parallel therewith, and one of the objects of the present invention is to make use of this fact

by providing each replacer with raised ribs 55 which by proper adjustment of the replacer-plate with reference to the displaced wheels act upon the flanges of said wheels to gradually adjust their direction of motion toward their respective rails as the car is pro- 60 pelled under its own power or by any other force.

Another object is to provide a pair of replacers which are identical in construction and capable of being interchanged or used 65 at opposite sides of their respective rails according to the direction of displacement of the wheels of the car.

A further object is to provide the replacer with a laterally swinging leader- 70 plate which is mounted upon a suitable supporting base and capable of adjustment to different angles relatively to their respective rails to correspond to the degree or direction of displacement of the wheels.

A still further object is to enable the swinging plate to be easily and quickly detached from the base and used for replacing the cars on rails where the surface of the pavement is substantially flush with that of the 80 ball of the rail.

Other objects and uses relating to specific parts of the replacer will be brought out in the following description.

In the drawings:

Figure 1 is a top plan of a portion of a railway track and a pair of my improved car replacers in operative position for replacing the displaced car wheels, portions of which are shown by dotted lines as just entering the replacers, the other dotted lines indicating the successive positions which the wheels assume in traveling along the replacer for replacement upon the rails.

Fig. 2 is a top plan of one of the same replacers as used at the inner side of the rail but in a reverse position end for end from that shown in Fig. 1.

Fig. 3 is a side elevation of the replacer shown in Fig. 2 and adjacent portion of the 100 rail.

Fig. 4 is an enlarged transverse sectional view taken on line 4-4, Fig. 2.

Fig. 5 is a top plan of a portion of the leader-plate of the replacer as used for replacing a car upon a rail the ball of which is substantially flush with the surface of the pavement.

As previously stated, in replacing a displaced car it is advisable to use two of the replacers, one for each wheel of the same axle, and therefore one of which is placed 5 at the inside of one rail and the other at the outside of the opposite rail according to the direction of displacement of the wheels on the same axle, and inasmuch as they are identical in construction the description of one replacer will be sufficient 10 for both except as to the angle of adjustment of the leader plates and the co-operation of their respective flanges in directing the displaced wheels toward and upon their 15 respective rails.

Each replacer comprises a supporting base 1—, a leader-plate 2—, a supplemental rail 3—, adapted to rest upon the ball of the rail of the track, and suitable means for 20 attaching the base 1— and supplemental rail 3— to the track rail "a."

The base 1— is symmetrical and tapered from one end toward its opposite end in top plan, and is wedge-shaped in side elevation, as shown more clearly in Figs. 1, 2, and 3, the narrower portion in plan being of 25 greatest vertical height in elevation so that as the width increases the height diminishes toward the end from which the wheels enter 30 the replacer.

The lower face of the base is substantially flat and when in active use is disposed in a horizontal plane substantially coincident with the lower face of the rail "a" so as to 35 rest firmly upon the ties either at the inside or outside of the rail in close proximity thereto according to the direction of displacement of the car wheels.

The upper face is disposed in an inclined 40 plane intersecting the lower face at a sharp angle at the widest end, the opposite end of the inclined face being disposed a distance above the plane of the upper face of the rail approximately equal to the radial depth 45 of the flange as "b" of the wheel as "B" to be replaced, whereby as the wheel rides up the incline of the leader-plate 2— presently described, its flange will be in a position to ride or slide laterally over the ball of the 50 rail.

For convenience of description, the wider end of the base 1—, which is also the thinnest end vertically, will be termed the rear end, while the opposite or horizontally 55 narrower and vertically deeper end may be termed the front, by reason of the fact that the car wheels move from the wider end toward the narrower end in replacing them upon the rails, although that direction of 60 movement is the reverse of that by which the wheels were displaced.

The front end terminates in a relatively narrow, flat extension 4—, the front end of which curves downwardly below the plane 65 of the rail, said extension being held in rela-

tively close proximity to one side of the rail by suitable fastening means hereinafter described.

The portion of the base upon which the plate 2— rests is substantially flat, but 70 the portion immediately in front of the front end of said plate is raised approximately the thickness of the plate just at the rear of the portion 4— and is provided with opposite upstanding flanges 5— rising from opposite edges thereof in horizontal spaced relation a distance corresponding approximately to the radial depth of the flange "b" of the wheel so that the tread of the wheel may ride on one or the other of 80 these flanges according to its position inside or outside of the rail, the space between the flanges 5— constituting a passageway for the flange of the wheel.

The leader-plate 2— is pivotally mounted upon the upper inclined face of the base 1— for laterally swinging adjustment and for this purpose is provided with a journaled bearing or opening 6— in its longitudinal center for receiving a pivotal stud 7—, 90 projecting upwardly from the upper face of the base 1—, the length of said plate being slightly greater than the distance from the rear ends of the ribs 5— to the rear end of the base 1—.

The lower and upper faces of the plate 2— are substantially flat and parallel except that the upper face is provided with a pair of upstanding lengthwise flanges 8— along its opposite edges and in spaced relation, the height of said flanges being approximately equal to or slightly greater than the radial depth of the flange "b" of the car wheel, so as to allow the tread of the wheel to ride upon either flange according 105 to the position of the replacer inside or outside of the rail.

The pivotal stud 7— passes through the longitudinal center of the plate 2— a short distance from its front end which latter travels in close proximity to the rear ends of the ribs or flanges 5— as the plate is adjusted about the axis of the pivot to bring its rear end into proper position for receiving the adjacent wheel preparatory to replacing the wheels upon the track. This plate is also tapered longitudinally from its rear end to its front end so that its opposite longitudinal flanges and also the flanges 8— diverge rearwardly, said ribs extending from points directly opposite the axis of the pivotal stud 7— to the extreme rear end of the plate and have their front and rear ends beveled laterally to better direct the flange of the wheel between them in case 115 it should strike the end of either rib, the object of the flanges being to form an intervening channel through which the wheel and particularly its flange may pass without liability of displacement from the plate 120 125 130

when the wheels are being replaced upon the track.

The portion of the plate —2— in front of the pivotal stud —7— is provided with 5 a central lengthwise rib —9— rising from the upper face thereof to a height corresponding approximately to the height of the ribs —5— and flanges —8— to additionally guide the wheel in its forward 10 movement and to form a bearing for the tread of the wheel as it passes along the replacer from the lower end to the higher end thereof.

The rear end of the rib or flange —9— 15 is spaced equal distance apart from the front end of both flanges —8— to form intervening channels for the passage of the wheel flange through either channel, depending upon the position of the replacer 20 inside or outside of the rail.

The supplemental rail —3— is adapted to rest upon the ball of the track rail “a” and is provided at one side with a pendant projection —10— for engaging the same side 25 of the track rail as that at which the replacer is located, said supplemental rail being provided with a laterally projecting lengthwise base flange —11— and an up- 30 standing rib or flange —12— rising above the flange —11— a distance equal to or slightly greater than the radial depth of 35 the wheel flange “b” so as to support the tread of the wheel and allow its flange to ride across the ball of the rail in the act of replacing the wheels upon the track.

This supplemental rail is also symmetrical in top plan to permit it to be used at either side of either rail according to the positions of the remaining portions of the 40 replacer, and is located directly opposite the front end of the base —1— where it together with the base is detachably held in fixed relation to the rail by means of a clamping bolt —13—, having one end ex- 45 tended across the ball of the rail through an opening —14— in the supplemental rail —3— and provided with a hook-shaped ex- 50 tremity —15— engaged with the face of the rail opposite that which is engaged by the projection —10—, the opposite end of the 55 clamping bolt —13— being provided with a threaded extension —16— passing through a vertical elongated opening —17— in the front end of the base —1— as shown more clearly in Fig. —4—, said extension being 60 provided with a transverse slot for receiving a tapered key —18— bearing against the extension —4— of the base, thereby locking said base in a fixed position with relation to the rail.

The projection —10— of the supplemental rail —3— is provided with vertical guide grooves —19— for receiving laterally projecting vertical ribs —20— on the adjacent 65 face of the extension —4— and permitting

the adjacent end of the base —1— to be adjusted vertically to conform to different heights of rails, this adjustment being permitted by the vertical elongation of the slot —17— in the extension —4— which latter 70 is provided with two sets of ribs —20—, one set at each side of the extension to permit the base to be locked to either the outside or inside of either rail by the same fastening means.

When the supplemental rail —3— is placed in operative position its raised rib or flange —12— extends parallel with the rail, the face of said rib at the side of the rail at which the corresponding wheel is displaced being disposed in substantially the same vertical plane as that of the corresponding side of the ball of the track rail while the opposite ends of the opposite side of said rib are beveled longitudinally so 85 that when the flange of the wheel is at that side, the beveled face will assist in forcing it across the ball of the track rail into proper replacement on the track, as shown more clearly by dotted lines in Fig. 1 in 90 connection with the replacer which is outside of the rail.

In order that the operation of my invention may be clearly understood I have shown by dotted lines in Fig. 1 relatively 95 small segments of the lower portions of the displaced wheel of one of the axles of the truck, the dotted line connecting segments indicating the axis of said wheels, said position indicating an extreme displacement at 100 which car replacers of almost any type would be effective, it being evident that when the two wheels on the same axis are displaced the flange of the wheel which is outside of the track will be much nearer its 105 corresponding rail than that of the other wheel to its rail and therefore the plates —2— are adjusted about their pivotal studs —7— with their rear ends corresponding distances from their respective rails to receive both wheels and when properly adjusted the front end of the rib —9— of the replacer at the inner side of the rail will be registered with the rib —5— nearest the rail while the central lengthwise rib —9— 110 of the other replacer will be registered with approximately the center of the space between the ribs —5— of the corresponding base.

Under the conditions of displacement 115 shown and the positions of the plates —2— as described, the wheel at the outside of the track is about to ride upon the rear end of the corresponding plate —2— while the other wheel is still some distance from the 120 rear end of its plate. A flange of the outside wheel will be aligned with the space between the rib —9— and flange —8— nearest the rail while the flange of the inside wheel will be in a line intersecting the flange 130

—8— of the corresponding place farthest from the rail so that as the car is propelled forwardly to the position indicated by the dotted line "R," the flange of the outside 5 wheel will have just entered the passage between the corresponding flanges —9— and —8— while the flange of the inside wheel will have encountered the inner face of the corresponding inner flange, and as 10 the car continues its movement to the position indicated by dotted line "S," the engagement of the flange of the inside wheel with the inner flange —8— will crowd both wheels toward their respective rails while 15 at the same time the overlapping of the flange of the inside wheel against the corresponding inner flange —8— tends to cause said wheel flange to parallel the replacer flange, thereby causing the outside wheel to 20 roll forwardly further up the incline and against the beveled rear edge of the rib or flange —5— of the corresponding base nearest the rail, which additionally crowds the wheels toward their respective rails as they 25 continue to roll up the incline of the plates —2—.

Now as the car continues to move forwardly to the position shown by the dotted line "T" the flange of the inside wheel will 30 pass between the flange —9— and innermost flange —8— of the corresponding plate while the flange of the outside wheel will pass to the inside of the innermost rib —5— of the corresponding replacer, thereby directing the flange toward the inner side of 35 the rear end of the rib —12— as shown by dotted line "U."

Now, as the axle with the wheels thereon continues to move to the position shown by 40 dotted line "V," the inclined rear end of the rib —12— of the outermost replacer will further crowd the wheels toward their proper positions on the track, causing the flange of the inside wheel to ride between 45 the ribs —5— of the corresponding replacer until it passes to the position shown by dotted line "W" where the flange of the outermost wheel will have dropped off from the corresponding replacer upon the ball of 50 the adjacent track rail, and owing to the tendency of the wheel flange to aline itself with the rail causes the opposite wheel to roll along its replacer rib —12— until it 55 assumes the position indicated by dotted line "X" at which time both wheels are properly replaced upon their respective rails.

From the foregoing description it will be seen that the inner rib —8— of the inside 60 replacer performs an important part in crowding the wheels toward the rails and in causing their flanges to pass through the proper channels of the replacer for carrying the ball of the outside wheel across the ball 65 of its rail aided by the rear inclined face of

the rib —12— of the outside replacer, but by duplicating these ribs —8— and —5— upon their respective parts permits the replacers to be interchanged at different sides of the tracks to accommodate the position 70 of the displaced wheels and also permits the replacers to be changed end for end according to the direction of movement of the car in replacing it.

What I claim is:

1. In a car replacer, in combination with a rail, a base section supported along one side of the rail and having a longitudinally inclined top face, a leader plate resting on said inclined face and hinged to swing laterally toward and from the rail and provided with raised ribs along its opposite edges in spaced relation and converging toward one end, and means for clamping the base to the rail.

2. In combination with a track rail, a car replacer comprising a base section having an inclined upper face, a clamping device adjustable horizontally on said section and provided with means for interlocking engagement with the ball of the rail, a leader section seated on said inclined face and hinged to swing laterally thereon, said leader section having spaced lengthwise ribs converging up the incline.

3. A car replacer comprising a base section having a longitudinally inclined upper face in combination with a leader plate hinged to swing laterally upon said face in the plane of said incline and provided with spaced lengthwise ribs converging toward the high end of the incline, and means attached to the higher end of the base section for securing said section to a track rail.

4. A car replacer comprising a base section having a longitudinally inclined upper face in combination with a leader plate hinged to swing laterally upon said face in the plane of said incline and provided with spaced lengthwise ribs converging toward the high end of the incline, said base having raised lengthwise ribs in spaced relation at the front end of the leader plate.

5. A car replacer comprising a base section having a longitudinally inclined upper face in combination with a leader plate hinged to swing laterally upon said face in the plane of said incline and provided with spaced lengthwise ribs converging toward the high end of the incline, and a supplemental rail having means for supporting it upon the ball of a track rail at the front end of said leader plate.

6. A car replacer comprising a base section having a longitudinally inclined upper face in combination with a leader plate hinged to swing laterally upon said face in the plane of said incline and provided with spaced lengthwise ribs converging toward the high end of the incline, and a supple- 130

mental rail having means for supporting it upon the ball of a track rail at the front end of said leader plate, and means for clamping the base and supplemental rail to the track rail.

7. A car replacer comprising, in combination with a track rail, a base supported along one side of the track rail and provided with a longitudinally inclined up-
10 per face, a supplemental rail mounted on the ball of the track rail at the higher end of

the base, and a leader plate mounted on said inclined face and provided with raised lengthwise ribs converging toward the supplemental rail.

15

In witness whereof I have hereunto set my hand this 2nd day of October, 1919.
